UNITED STATES PATENT OFFICE.

JAKE KARLAN, OF NEW YORK, N. Y.

METHOD OF MAKING FINGER RINGS.

Application filed March 10, 1923. Serial No. 624,216.

To all whom it may concern:

Be it known that I, JAKE KARLAN, a citizen of the United States, and a resident of New York city, county and State of New York, have invented certain new and useful Improvements in Methods of Making Finger Rings, of which the following is a specification.

This invention relates to finger rings and particularly to methods of making rings.

One of the objects of the invention is to provide a simple, practical and inexpensive method of making finger rings.

Another object of the invention is to provide a method of making rings that will involve the use of a minimum amount of material.

Further objects of the invention will appear from the following description taken in connection with the drawings which form a part of this application and in which,

Fig. 1 is a plan view of one form of blank that may be used in the method of making the rings.

Fig. 2 shows the blank of Fig. 1 folded into position for soldering or otherwise joining the meeting edges of the blank.

Fig. 3 is an elevation view of a ring formed in the manner illustrated in Figs. 1 and 2.

Fig. 4 is a plan view showing another form of blank that may be utilized in carrying out the invention.

Fig. 5 shows the blank of Fig. 4 in folded position.

Fig. 6 is an elevational view of a ring formed from the blank shown in Figs. 4 and 5.

Fig. 7 is a plan view of another form of blank that may be utilized in carrying out the invention.

Fig. 8 shows the blank of Fig. 7 in folded position.

Fig. 9 is an elevational view partly in section showing a ring formed from the blank illustrated in Figs. 7 and 8.

Figs. 10 and 11 are plan views of bezels that may be used in the ring illustrated in Fig. 9, and

Fig. 12 is an elevational view illustrating a portion of another form of ring constructed in accordance with the invention.

The invention briefly described involves the use of a stamped metal blank having an elongated relatively narrow intermediate portion and end portions extending laterally

with respect to the intermediate portion. The intermediate portion is bent into a substantially circular shape forming the band and the end portions are bent transversely to form the crown of the ring. In certain forms of the invention the end portions are formed on opposite ends of the elongated intermediate portion and extend in opposite directions with respect to each other. This is true of the forms shown in Figs. 1 and 7. In the other form illustrated in Fig. 4 the end portions which form the crown are formed at the same end of the elongated intermediate portion and extend laterally therefrom on opposite sides thereof. When the elongated strip has been bent into substantially circular form and the end portions have been bent around to form the pocket or crown the meeting edges are joined in any suitable manner as by soldering. Further details of the invention will appear from the following description.

In the form of the invention illustrated in Figs. 1-3 inclusive, the blank comprises an elongated relatively narrow intermediate strip 10 and laterally extending end portions 11 and 12 disposed at the opposite ends of the portion 10 and extending in opposite directions from each other. This blank can be formed by a single operation in a stamping machine and to form the ring the blank is bent as illustrated in Fig. 2. The intermediate portion 10 forms the band of the ring and the end portions 11 and 12 are bent around to the positions illustrated in Fig. 2 wherein the edge 13 of the portion 11 is disposed adjacent the edge 14 of the portion 12 and wherein the edge 15 of the portion 11 is disposed adjacent the edge 16 of the portion 12. These meeting edges can then be joined in any suitable manner as by soldering.

Fig. 3 illustrates a form of ring that may be made in the manner just described and in this ring the end portions 11 and 12 are ornamented or adorned with filigree 17. This filigree may be formed by the stamping machine.

In Figs. 4, 5 and 6 the blank comprises an elongated portion 20 having flared ends 21 and 22 and laterally extending end portions 23. The portions 23 extend laterally in opposite directions from the same end of the intermediate portion 20. To form the ring from the blank shown in Fig. 4, the blank is bent as illustrated in Fig. 5 and the portions

23 are also bent to form the pocket or crown. In this instance the outer edges 25 are joined to the end 21 of the strip 20 and the inner edges 26 of the end portions are joined 5 to the end 22 of the strip 20.

The form of the invention illustrated in Figs. 7, 8 and 9 is somewhat similar to that shown in Figs. 1 and 3 and in this form of the invention the blank comprises an elongated strip 30 having flared ends 31 and 32 and the end portions 33 and 34 which form the crown extend laterally from the opposite ends of the strip 30 and in opposite directions with respect to each other. To form a 10 ring from the blank shown in Fig. 7 the blank is bent as shown in Fig. 8 forming the band and the end portions 33 and 34 are bent transversely to form the crown or pocket. In this instance the edges 35 and 15 36 of the portions 33 and 34 are connected to the adjacent edges 37 and 38 of the ends 31 and 32 of the elongated portion and the edges 39 and 40 are connected respectively to the edges 41 and 42 of the ends 31 and 32 20 of the elongated portion.

In Figs. 10 and 11 are shown bezels 50 and 51 which may be secured in the crown of the ring illustrated in Figs. 7 and 8 or if desired in the other forms of the ring illustrated. These bezels are shown in Fig. 9 30 in section.

Fig. 12 illustrates another form of ring 60 constructed in accordance with the invention. This ring is formed in a manner similar to those above described but the crown is disposed at an angle to the band necessitating angular bends in the forming of the ring.

Although certain specific embodiments of 40 the invention have been particularly illustrated and described it will be understood that the invention is capable of further modification and that further changes in the construction and in the arrangement of 45 the various cooperating parts may be made without departing from the spirit or scope of the invention as expressed in the following claims.

What I claim is:—

50 1. A method of making a finger ring which consists in forming a single piece blank having an elongated portion adapted to form the band and end portions adapted to form the crown of the ring, bending the 55 elongated portion into a portion of a circle and folding the end portions transversely with respect to the elongated portion to form the crown.

2. A method of making a finger ring 60 which consists in forming a single piece blank having an elongated portion adapted to form the band and end portions adapted to form the crown of the ring, bending the 65 elongated portion into a portion of a circle and folding the end portions transversely

with respect to the elongated portion into meeting position to form the crown.

3. A method of making a finger ring which consists in forming a single piece blank having an elongated portion adapted 70 to form the band and end portions adapted to form the crown of the ring, bending the elongated portion into a portion of a circle and folding the end portions transversely with respect to the elongated portion into meeting position and joining the meeting edges to form the crown.

4. A method of making finger rings which consists in forming a stamped metal blank having an elongated intermediate portion adapted to form a band, and end portions extending laterally therefrom, bending the intermediate portion into a portion of a circle and folding the end portions to 80 form a pocket.

5. A method of making finger rings which consists in forming a stamped metal blank having an elongated intermediate portion adapted to form a band, and end portions extending laterally therefrom, bending the intermediate portion into a portion of a circle 90 and folding the end portions to form a pocket with the edges thereof disposed in proximity to each other, and joining said edges.

6. A method of making finger rings which consists in forming a stamped metal blank having an elongated intermediate portion adapted to form a band, and end portions extending laterally therefrom at each 100 end thereof, bending the intermediate portion into a portion of a circle and folding the end portions to form a pocket.

7. A method of making finger rings which consists in forming a stamped metal blank having an elongated intermediate portion adapted to form a band and end portions extending laterally therefrom at each end thereof, the end portions at one end extending in a direction opposite to the end portion at the other end of the intermediate portion, bending the intermediate portion into a portion of a circle and folding the end portions to form a pocket.

8. A method of making finger rings which 115 consists in forming a stamped metal blank having an elongated intermediate portion adapted to form a band, and end portions extending laterally therefrom, in opposite directions, bending the intermediate portion into a portion of a circle and bending the end portions to form a pocket.

9. A finger ring blank having an elongated, relatively narrow intermediate portion adapted to form the band of the ring 125 and laterally extending end portions adapted to form the crown of the ring.

10. A finger ring blank having an elongated, relatively narrow intermediate portion adapted to form the band and end por- 130

tions extending laterally therefrom in opposite directions adapted to form the crown.

11. A finger ring blank having an elongated, relatively narrow, intermediate portion adapted to form the band and end portions extending laterally therefrom in opposite directions at the opposite ends of the elongated portions adapted to form the crown.

12. A method of making finger rings which consists in forming a stamped metal blank having an elongated portion adapted to form a band, and end portions extending laterally therefrom, bending the elongated portion into a portion of a circle and folding the end portions to form a pocket.

13. A finger ring blank having an elongated, relatively narrow, intermediate portion adapted to form the band of the ring and laterally extending end portions at each end thereof adapted to form the crown of the ring.

14. A finger ring blank having an elongated, relatively narrow intermediate portion adapted to form the band of the ring

and laterally extending end portions adapted to form the crown of the ring, said end portions having edges curved to cooperate with the intermediate portion in completing the circular band of the ring.

15. A finger ring blank having an elongated, relatively narrow, intermediate portion adapted to form the band and end portions extending laterally therefrom in opposite directions adapted to form the crown, said end portions having edges curved to cooperate with the intermediate portion in completing the circular band of the ring.

16. A finger ring blank having an elongated, relatively narrow, intermediate portion adapted to form the band and end portions extending laterally therefrom in opposite directions at the opposite ends of the elongated portions adapted to form the crown, said end portions having edges curved to cooperate with the intermediate portion in completing the circular band of the ring.

In witness whereof, I have hereunto set my hand this 8th day of March, 1923.

JAKE KARLAN.
